(57) **CLAIM**

The ornamental design for an air cleaner element lifting shaft for vehicle, as shown and described.

DESCRIPTION

FIG. 1 is a perspective view of an air cleaner element lifting shaft for vehicle;

FIG. 2 is a front view of the air cleaner element lifting shaft for vehicle shown in FIG. 1;

FIG. 3 is a rear view of the air cleaner element lifting shaft for vehicle shown in FIG. 1;

FIG. 4 is a left side view of the air cleaner element lifting shaft for vehicle shown in FIG. 1;

FIG. 5 is a right side view of the air cleaner element lifting shaft for vehicle shown in FIG. 1;

FIG. 6 is a top view of the air cleaner element lifting shaft for vehicle shown in FIG. 1; and,

FIG. 7 is a bottom view of the air cleaner element lifting shaft for vehicle shown in FIG. 1.

1 Claim, 4 Drawing Sheets
